UNITED STATES PATENT OFFICE.

JOHN W. HICE, OF JOHNSON CITY, TENNESSEE.

APPARATUS FOR AND METHOD OF BENDING AND SETTING STOCK.

Specification of Letters Patent. Patented Dec. 29, 1914.

1,122,750.

Application filed May 28, 1914. Serial No. 841,580.

To all whom it may concern:

Be it known that I, JOHN W. HICE, a citizen of the United States, residing at Johnson City, in the county of Washington and State of Tennessee, have invented new and useful Improvements in Apparatus for and Methods of Bending and Setting Stock, of which the following is a specification.

This invention relates to apparatus for 10 and method of bending and setting stock, the same being especially designed for use in the formation and construction of curved wooden structures such as wheel rims and felloes, table rims or aprons and other similar wooden articles.

One of the objects of the present invention is to provide a quick and easy method of bending and setting wood rims and the like, enabling the same to be removed from 20 the bending machine as rapidly as they are bent into shape, also to enable the work to be performed in a better and more accurate way and without the necessity of cutting the strips or laminations of the rim to care- 25 fully graduated lengths in order to obtain the end pressure now employed in the manufacture of such articles.

A further object of the invention is to provide means whereby the uniform pressure 30 sure between all the sections or laminations of the stock is maintained throughout the entire length thereof after the bent stock is removed from the machine.

With the above and other objects in view, 35 the invention consists in the novel construction, combination and arrangement of parts, as will be hereinafter more fully described, illustrated and claimed.

In the accompanying drawings:—Figure 40 1 is a front elevation of a sufficient portion of a wood bending machine to illustrate the relation of the present invention thereto, the bending arms and stock being illustrated in their initial positions. Fig. 2 is 45 a similar view showing the position of the bending arms and the condition of the stock just before the arms have reached their final positions. Fig. 3 is a similar view showing the final position of the parts. 50 Fig. 4 is a detail edge view of the stock showing the manner of combining the plies or laminations. Fig. 5 is a front elevation of the bent stock and the setting or restraining means therefor after removal from the 55 bending machine. Fig. 6 is a detail perspective view on an enlarged scale of the

pressure distributing bar. Fig. 7 is a detail view of one end of said bar. Fig. 8 is a detail perspective view of one end of a bar provided with offsetting springs. Fig. 60 9 is a fragmentary perspective view of the form showing the same provided with offsetting springs. Fig. 10 is a detail elevation showing the initial relation of the spring supported bar to the form preparatory to the application of pressure lengthwise of the inner ply. Fig. 11 is a similar view showing another position of the bar. Fig. 12 is a detail perspective view of a longitudinally extensible pressure distributing 70 bar. Fig. 13 is a fragmentary longitudinal section of the same. Figs. 14, 15 and 16 are detail views showing different forms of teeth or spurs for the pressure distributing bar.

The bending machine, in the main, is of the usual construction and operation and therefore only needs sufficient description to enable the present invention to be understood. In the drawings, the machine is seen 80 to comprise the usual base or bed plate 1, the upright central frame 2, the form 3 which is fastened to the upright portion 2 of the frame and adjustable by means of a bolt 4, and a pair of bending arms or levers 85 5 along the working faces of which extends a continuous master strap 6 upon which the stock is placed preparatory to the bending operation, each of said arms being provided with a head block 7 which is adjustable longitudinally thereof in accordance with the 90 length of the stock.

In carrying out the present invention, a number of rims are adapted to be simultaneously bent by the machine and the strips 95 or plies of said rims are assembled in the manner illustrated in the detail edge view, Fig. 4, wherein it will be observed that three superimposed rim structures are placed one upon the other, each rim embodying the 100 plies or laminations *a*, *b* and *c*, the adjacent faces of the plies *a* and *b* being coated with adhesive material such as glue, and the adjacent faces of the plies *b* and *c* being correspondingly treated. The spaces indicated 105 by the lines *d* between the rim structures are not coated with adhesive material so that they are readily separated from each other when removed from the restraining means hereinafter particularly described. It is 110 the ordinary practice to also arrange several series of superimposed rims, the bend-

ing machine being ordinarily of sufficient width to contain three tiers or piles of rims thus enabling nine complete laminated rims to be bent simultaneously in one complete 5 operation of the machine.

The stock indicated generally by the character A in Fig. 1 is primarily placed on the master strap 6 and beneath the form 3 and between the stock A and the master strap 6 there is placed a restraining band 8 which is best illustrated in Fig. 5. This restraining band is of sufficient length to extend around the outer face of the stock and has its opposite ends inserted between a pair of clamping plates or members 9 and 10 which are subsequently bolted or otherwise permanently fastened together, said members 9 and 10 together forming an end block. Two 10 of such end blocks are employed, one being fastened to each end of the restraining band 8 and each block is furthermore provided with an extending stud 11. These studs 11 are adapted to be connected by a shackle designated generally at B and consists of two relatively overlapping sections 12 and 13 provided at their outer ends with sleeves 14 which may be readily slipped over the studs 11, the head blocks 7 hereinabove referred to being recessed in their inner 15 faces to receive the sleeves 14 and studs 11. The shackle members 12 and 13 are provided with longitudinal series of perforations 15 to receive a connecting pin 16 which is also preferably inserted through a collar 17 slidable lengthwise of the members 12 and 13 as shown in Fig. 5.

C generally designates a pressure distributing bar, the preferred embodiment of which is illustrated in Fig. 6 wherein it will be observed that said bar comprises a board 18 the length of which is sufficient to extend diametrically between the end portions of the stock A as shown in Fig. 5. The bar is provided at its opposite extremities with 20 projecting spurs or teeth 19 which are preferably formed on a face plate 20 fastened as shown at 21 to the bar. The construction just referred to is not, however, essential as the board 18 itself may be formed of metal as indicated in Fig. 16 at 18' in which case the spurs or teeth 19' may be formed integrally with the metal bar itself. Instead of forming the teeth as shown in Figs. 6 and 16, the teeth indicated at 19'' may be 25 inserted into the end of the wooden board 18'' as shown in Fig. 15. Instead of forming the teeth as shown in Fig. 16 wherein they are in the shape of pointed barbs, said teeth may be formed after the manner of a rasp surface as indicated in Figs. 7 and 14, 19''' indicating said rasplike teeth. In the preferred embodiment of this feature of the invention it is also preferred to provide the board 18 with end risers 22 which may be 30 either substantially wedge-shaped as shown

in Fig. 6 or substantially rectangular as shown at 22' in Fig. 7 and it is also preferred to mount a wear plate 23 on each of the risers, against which wear plate one of the end blocks 10 rides as said end blocks 70 are moved inwardly. As the end blocks are moved inwardly by the bending arms 5 of the machine, the said end blocks ride against the wear plates 23 and exert a downward pressure on the board 18 the teeth 19 of 75 which are in engagement with the inner face of the stock A at diametrically opposite points as illustrated in Fig. 5. This produces lengthwise pressure in both directions on the inner ply or plies of the stock 80 A and causes a uniform radial outward pressure on the superimposed laminations or plies upon each other, all of said plies being restrained by the band 8. This pressure takes place during the bending operation 85 performed by the machine and when the final limit of movement of the machine is reached as shown in Fig. 3, the shackle B is slipped over the studs 11 and tightened by the adjusting means hereinabove 90 described. In this way the pressure just hereinabove described is maintained after the bending arms have been returned to their initial positions and said pressure is still maintained after the bent stock is removed 95 from the machine.

To facilitate the removal of the bent stock from the machine, the form 3, as best illustrated in Figs. 1, 2 and 9, comprises in addition to the main body 24, a facing plate 25 100 comprising two hinged end sections 26 which are secured to the outer side of links 27 pivotally connected at 28 to the main body 24 of the form. These links 27 are in turn pivotally connected to a pair of inwardly 105 extending connecting rods 29 and said rods are pivotally attached to the hub of a hand lever 30 by the movement of which the hinged end sections 26 of the form may be drawn inwardly thereby contracting a sufficient portion of the form to enable the bent stock to be readily removed therefrom together with the bar C, the restraining band 8, the members 9, 10, and the connecting shackle. The machine is then ready to receive a new batch of rims.

Under the arrangement hereinabove described and as illustrated in Figs. 1 to 7 both inclusive, in associating the bar C with the stock, one or both extremities of said bar are 115 slightly elevated above the form 3 as shown in Fig. 2 before lengthwise pressure is applied to the stock so that when said pressure is applied, there can be a sufficient amount of movement of the bar C toward 120 the form to effect the pressure on the inner ply or plies of the stock. Another way of accomplishing the same result is illustrated in Figs. 8 to 11 both inclusive in which use is made of offsetting or spacing springs 31 130

which may either be applied to the bar C as shown in Fig. 8 or to the form 3 as indicated in Fig. 9 where said springs are designated 31'. These springs may be utilized at one end of the bar or form as shown in Fig. 10 or at both ends thereof as shown in Fig. 11, the result being the same in each case, namely, a sufficient space is left between one or both ends of the bar and the form to allow for a sufficient movement to obtain the necessary pressure on the inner ply or plies of the stock A. It is in this way that a uniform outward radial pressure is obtained between the inner ply or plies and those lying outside thereof, such outward radial pressure being resisted by the restraining band 8.

In Figs. 12 and 13 I have illustrated another form of bar C which is composed of two relatively movable sections 32 and 33 having reversely tapered inner adjacent edges 34 and 35 between which is a spreading or expanding wedge 36, operated by means of an adjusting or feed screw 37 which may be turned by a suitable wrench 38, the latter being shown in the form of an ordinary socket wrench detachably applied to a squared end 39 of the screw 37. The screw 37 is journaled in a bearing plate 40 overlapping the side edges of the cap sections 32 and 33, said sections being connected by splice bars 41 which are connected to the sections of the bar C by means of bolts 42 or their equivalent which work in conjunction with slots 43 in one or both of the sections 32 and 33 of the cap board. The pressure bar sections are shown as provided at their opposite extremities with spurs or teeth 44 corresponding in function with the spurs or teeth 19 hereinabove described. In the use of the longitudinally extensible bar C, said bar is first contracted in length and is then expanded after being interposed between the end portions of the stock so as to occupy the same relation thereto as is shown in Fig. 5. In view of the foregoing description taken in connection with the accompanying drawings it will now be understood that the ordinary wood bending machine is employed to bend the laminated rims into their final condition and that during such bending movement lengthwise pressure is applied in both directions to the inner ply or plies of the rims by means of the cap board which obtains a positive engagement with the stock and which is acted upon by the end blocks in turn acted upon by the head blocks on the bending arms, thereby exerting an outward radial pressure on all of the plies or laminations so as to obtain good contact between all of the glued surfaces of the plies which will prevent subsequent splitting and breaking down of the glued joints. Furthermore, and of great importance, it will be understood that the pressure referred to is maintained after the bending arms of the ma-

chine have been moved back to their initial positions and also maintained after the bent stock has been entirely removed from the machine.

The method hereinabove described may be carried out quickly and with absolute accuracy and it insures efficient glued joints throughout the entire contacting area of the plies or laminations. Furthermore, it does away with the necessity of carefully graduating the lengths of the laminations in order to obtain lengthwise pressure which has hitherto been produced by causing the head blocks 7 to bear directly against the extremities of the plies or laminations. 80

What I claim is:—

1. In a bending machine, the combination with a form, and means for bending the stock around said form, of a restraining band adapted to be simultaneously bent around the outside of the stock, a bar insertible between the ends of the stock, and adapted to terminally engage the end portions of the inside ply and move in a direction lengthwise of the stock, and end blocks 90 on said band adapted to press against said bar.

2. In a bending machine, the combination with a form, and means for bending the stock around said form, of a restraining band adapted to be simultaneously bent around the outside of the stock, a bar insertible between the ends of the stock and provided with teeth for positively engaging the inside ply of said stock, and adapted 100 to exert lengthwise pressure on said inside ply, and end blocks on said band adapted to press against said bar.

3. In a bending machine, the combination with a form, and means for bending the stock around said form, of a restraining band adapted to be simultaneously bent around the outside of the stock, a bar insertible between the ends of the stock and provided with teeth for positively engaging 110 the end portions of the inside ply of said stock, and exerting a lengthwise pressure on said inside ply, end blocks on said band adapted to press against said bar, and a shackle for connecting said end blocks. 115

4. In a bending machine, the combination with a form, and means for bending the stock around said form, of a restraining band adapted to be simultaneously bent around the outside of the stock, a bar insertible between the ends of the stock, and adapted to terminally engage the end portions of the inside plv and move in a direction lengthwise of the stock, risers on the opposite ends of said bar, and end blocks 120 on said band adapted to press against said risers.

5. In a bending machine, the combination with a form, and means for bending the stock around said form, of a restrain- 130

- ing band adapted to be simultaneously bent around the outside of the stock, a longitudinally extensible bar insertible between the ends of the stock and provided with 5 means for positively engaging the inner surface of the inside ply of said stock, and exerting a lengthwise pressure on said inside ply, and end blocks on said band adapted to press against said bar.
- 10 6. In a bending machine, the combination with a form, and means for bending the stock around said form, of a restraining band adapted to be simultaneously bent around the outside of the stock, a bar insertible between the ends of the stock, and 15 adapted to terminally engage the end portions of the inside ply and move in a direction lengthwise of the stock, end blocks on said band adapted to press against said bar,
- 20 and yieldable spacing means between said form and bar.
7. The combination with freshly bent stock, of means for maintaining such stock in its bent condition, said means comprising 25 a bar having means at its opposite extremi-
- ties to positively engage the inner ply of the stock, a restraining band extending around the outer face of the stock, and means associated with the opposite extremities of said band and bar board causing the latter to press the inner ply of stock outwardly to effect a uniform outward radial pressure on all plies of said stock.
8. The method of bending and setting laminated stock, consisting in bending said stock around a form, exerting lengthwise pressure in opposite directions on the inside 35 ply only of the stock by engaging the inner surface of said ply to effect a uniform outward radial pressure on the superimposed 40 plies, and removing the stock from the form while still maintaining the stock under such pressure.

In testimony whereof I affix my signature in presence of two witnesses.

JOHN W. HICE.
